United States Patent [19]

Nagai et al.

[11] Patent Number: Des. 303,095

[45] Date of Patent: ** Aug. 29, 1989

[54] AUTOMATIC CHEMICAL ANALYZER

[75] Inventors: **Yawara Nagai, Hachioji; Shigeru Yoshinari; Masao Ushikubo**, both of Tokyo, all of Japan

[73] Assignee: **Olympus Optical Co., Ltd., Japan**

[**] Term: 14 Years

[21] Appl. No.: 852,918

[22] Filed: Apr. 16, 1986

[52] U.S. Cl. D10/81; D24/1.1

[58] Field of Search D10/46, 81; D24/1.1, D24/8, 17, 21; 422/63-67; 356/39-41

[57] CLAIM

The ornamental design for an automatic chemical analyzer, as shown and described.

DESCRIPTION

FIG. 1 is a front, top, and left side perspective view of an automatic chemical analyzer, showing our new design;

FIG. 2 is a rear, bottom, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof.
